UNITED STATES PATENT OFFICE

2,421,478

FIBER CONDITIONER

John Blewett, Dallas, Tex., assignor to The
Murray Company, Dallas, Tex.

Application December 21, 1943, Serial No. 515,095

4 Claims. (Cl. 19—93)

1

This invention relates to new and useful improvements in fiber conditioners and particularly cotton cleaners.

One object of the invention is to provide an improved fiber conditioner which efficiently and thoroughly conditions fiber by removing therefrom extraneous matter, such as green leaf, in a substantially whole or intact state, whereby breaking of the extraneous matter and admixing of the same with said fiber is reduced to a minimum.

An important object of the invention is to provide an improved fiber conditioner, such as a cotton cleaner, having means for accommodating the discharge of extraneous matter separated from the fiber in a substantially whole or intact state, there being means for urging the extraneous matter toward and through the discharge means so as to materially decrease the length of time necessary for conditioning the fiber.

A particular object of the invention is to provide an improved fiber conditioner having a discontinuous, grate-type cleaning surface with rotating elements adjacent to and coacting therewith for receiving the fiber therebetween so as to separate and discharge extraneous matter from said fiber, together with means for inducing an air current or stream through the conditioner for urging the extraneous matter into and maintaining the same in engagement with the cleaning surface, whereby said extraneous matter will be separated from the fiber and forced through the discontinuities of said cleaning surface by the interdependent coaction of the cleaning surface, elements and air stream.

Another object of the invention is to provide a fiber conditioner, of the character described, having a cleaning chamber which includes an improved cleaning surface of the discontinuous, grate-type having openings for discharging small extraneous matter and for receiving portions of larger extraneous matter separated from the fiber, the cleaning surface also having additional openings disposed transversely of and communicating with the first-named openings for receiving the larger extraneous matter therefrom and discharging the same from the cleaning chamber, said extraneous matter being urged into and through the openings by an air stream or current.

2

A further object of the invention is to provide an improved cleaning surface for the cleaning chamber of a fiber conditioner, which surface includes a plurality of longitudinally and transversely spaced fingers extending longitudinally of the chamber and forming openings for accommodating the discharge from said chamber of extraneous matter separated from the fiber, the extraneous matter of greater area than the longitudinal openings being moved along the fingers by the wiping action of rotating elements toward the transverse openings for discharge therethrough by an air stream or current.

Still another object of the invention is to provide an improved fiber conditioner, of the character described, wherein green leaf and other extraneous matter are removed from the fiber in a minimum amount of time and with a minimum amount of cleaning action by the coaction 15 of a cleaning surface, a rotating element and a downwardly-directed air current, whereby the efficiency of the conditioner is materially increased without enlarging the size thereof or the number of rotating elements and without depending upon 20 the beating action of the elements so as to eliminate roping, twisting and machining of the fiber; the extraneous matter being preferably wilted to a soft, flexible or pliable condition prior to the introduction of the fiber into said conditioner and the air being preferably dry and hot.

A construction designed to carry out the invention will be hereinafter described together with other features of the invention.

The invention will be more readily understood 35 from a reading of the following specification and by reference to the accompanying drawings, wherein an example of the invention shown, and wherein:

Figure 1 is a longitudinal sectional view of a 40 fiber conditioner or cotton cleaner constructed in accordance with the invention,

Figure 2 is an enlarged plan view of a transverse portion of the cleaning surface of the cleaning chamber,

Figure 3 is an enlarged elevation of a portion 45 of one of the longitudinal reinforcing members, showing the adjustable mounting of the sleeve sections which carry the fingers of the cleaning surface, and

Figure 4 is an enlarged, isometric view of one

of the fingers and showing the relation thereof to its sleeve section.

In the drawings, the numeral 19 designates a conditioner or cleaner which is adapted to clean cotton and which may be of any desired construction, such as the horizontal cylinder type. The cleaner includes a chamber 11 into one end of which the cotton to be cleaned is introduced through a suitable inlet 12. A plurality of spaced, horizontal cleaning cylinders or elements 13 are mounted transversely within the chamber and are disposed over concave cleaning surfaces 14, each surface being swung on an arc substantially concentric to the shaft of its respective cylinder and coacting with the other surfaces to form an undulating bottom for the chamber 11. The cylinders rotate in a counter-clockwise direction so as to carry the cotton from the inlet 12 over the cleaning surfaces 14 to a suitable discharge outlet 15 which communicates with the far or opposite end of the chamber. Although the cylinders may be of any suitable construction, the same are preferably of the type shown in United States Letters Patent No. 2,096,955, issued to me on October 26, 1937. A vacuum discharge wheel 16 is preferably interposed between the chamber and the outlet 15 for preventing the discharge of air from said chamber with the cotton.

This air is delivered to the chamber in a current or stream by means of a pipe (not shown) which communicates with a transition 17, the transition being connected to a flared hood or spreader 18 which in turn overlies the cleaner and communicates with said chamber. It is pointed out that the spreader is of such size as to communicate directly with the major portion of the cross-sectional area of the chamber 11, thereby causing the air current to be spread substantially throughout the entire area of said chamber. A suitable hopper 19, having a discharge duct (not shown) connected thereto, is connected to the bottom of the cleaner so as to communicate with the chamber for receiving the air which flows therethrough and the extraneous matter separated from the cotton and passing through the cleaning surfaces 14.

Frequently, the cotton to be cleaned is seed-cotton which has been gathered or harvested by mechanical apparatuses and consequently contains an excessive quantity of green leaves as well as other extraneous matter. Although a cleaner of the standard type will satisfactorily remove most of the extraneous matter from the cotton, said cleaners are ineffective insofar as the removal of the green leaves is concerned. In order to efficiently remove these green leaves as well as other large extraneous matter without damaging the cotton, such as by excessive roping, twisting and machining, a new type of cleaning surface has been conceived and will herein-after be more fully described. It has been found that the efficiency of a cleaner having such a cleaning surface is increased by reducing the green leaves and other extraneous matter to a soft, flexible or pliable condition and this may be accomplished by drying the cotton so as to wilt said leaves. It is also noted that it is desirable for the air stream within the cleaning chamber 11 to be relatively dry and hot so as to further wilt the leaves within said chamber. If desired, this air may be the same air that is used to dry the cotton and which is subsequently separated from said cotton as shown in my co-

pending application, Serial No. 515,094, filed December 21, 1943.

Each cleaning surface is of the discontinuous, grate-type and includes a plurality of arcuate fingers or elements 20 which are circular in cross-section and which are preferably swung on an arc of greater radius than the cylinders 13. As is clearly shown in Figure 2, the fingers 20 are disposed in spaced, parallel rows which extend transversely of or across the cleaning chamber 11 and each finger is preferably disposed in the same vertical plane as the contiguous fingers of the adjacent rows, whereby said fingers are aligned. Each transverse row of fingers is welded or otherwise secured to a sleeve 21 (Fig. 3) which is journaled or telescoped upon an elongate, transverse bolt or rod 22. If desired, each sleeve 21 may be divided into several relatively short sections 23, although each bolt 22 extends entirely across the cleaning chamber with the usual head 24 formed on one end and a nut 25 screw-threaded upon the other end thereof.

In order to support the bolts 22 and to permit the use of relatively small diameter material, a plurality of thin, vertical, plates or ribs 26 extend longitudinally beneath the chamber 11 in spaced, parallel relationship and have suitable spaced openings formed adjacent their upper marginal edge portions for receiving said bolts. As is clearly shown in Figure 3, the upper marginal edge portion of each rib 26 is complementary to the concave cleaning surfaces 14, being undulating so as to have concave portions 27. The arc of each portion 27 is of greater radius than the radius of its overlying cylinder 13 and of lesser radius than the arc of its underlying cleaning surface or the fingers 20, whereby said portion is interposed therebetween. The ribs 26 extend entirely across the chamber beyond the open upper end of the hopper 19 and preferably have their ends connected to the end walls of the cleaner.

For vertically adjusting the fingers, a short flat arm or ear 28 is mounted on each end of each sleeve section 23 so as to extend contiguous and parallel to the ribs 26. A transverse slot 29 is formed in the outer or free end of each arm 28 for receiving a short bolt 30 which also extends through a suitable opening formed in the rib contiguous to said arm. Although these openings are disposed adjacent the upper marginal edge portion of their respective ribs, each opening is located below its respective large bolt opening. Thus, the position of the fingers may be adjusted by moving the arms 28 relative to the bolts 30 and the bolts which pass through the intermediate ribs may each receive a pair of arms, one on each side of each rib for adjustably fastening the same to said rib. Due to the undulating upper marginal edge portions of the ribs, it is manifest that neither the large bolt openings nor the short bolt openings are horizontally aligned. However, the corresponding openings of the ribs are in transverse, axial alignment and the corresponding openings of each rib are horizontally aligned, whereby the cleaning surfaces 14 are identical as are the portions of each surface between said ribs.

Each finger 20 is of such length that the outer ends of the fingers of each row will barely clear the inner portions of the aligned fingers of the contiguous, parallel row which are fastened to the adjacent sleeve section 23, said free or outer ends being preferably bevelled upwardly and outwardly as shown at 32. It is noted that the

most desirable position of the fingers is best shown in Figure 3, wherein the bevelled end 32 of each finger is spaced a slight distance above the inner portion of the contiguous finger of the adjacent row so that a contracting throat or space 33 is provided therebetween for accommodating the passage of green leaves as well as other large extraneous matter. Manifestly, this position of the fingers is attained by properly adjusting the arms 20. Attention is directed to the fact that the contracting spaces are accentuated by the projecting portions of the cylinders 13 which pass in close proximity thereto.

As has been hereinbefore set forth, the seed-cotton, frequently containing green leaves and other large extraneous matter which are preferably in a soft, flexible or pliable condition, is delivered to the cleaning chamber 11 of the cleaner 10 through the inlet 12 and passes to the left of and beneath the left-end cylinder 13. The counter-clockwise rotation of the cylinders carries or causes the cotton to travel longitudinally and toward the right of the chamber, over the cleaning surfaces 14 and beneath said cylinders. During this movement of the cotton, the motes, dirt and other small extraneous matter or trash will fall through the longitudinal spaces between the fingers 20. The green leaves, being larger than the spaces between the fingers, ordinarily will not pass through said spaces; however, the air which flows vertically through the chamber from the spreader 18 to the hopper 19 will cause the leaves to adhere or cling to the fingers so that portions of each individual leaf will be forced partially into these longitudinal spaces. Due to the soft, flexible or pliable condition of the green leaves, very little force is required to bend or fold each leaf upon itself and the air stream has sufficient force to accomplish such bending or folding. Thus, it is manifest that a considerable proportion of the leaves will be bent or folded and forced through the longitudinal spaces of the cleaning surfaces 14 instead of adhering or clinging to the fingers. Obviously, the wilting of the leaves will tend to prevent the same from bridging the fingers so as to permit discharge of the same. If relatively hot air, approximately 180° F., is employed for a short period of time, as is preferable, it will tend to further increase the flexibility of the leaves. The wiping action of the cleaning cylinders will move each green leaf, which bridges the fingers, longitudinally of said fingers, from the ends of which said leaf will be shed or stripped and drawn through the contracting throats 33 by the air current. Of course, other large extraneous matter or trash also will be forced together with the wilted green leaves through the throats 33 and the longitudinal spaces by the combined action of the downwardly-directed air current and the counter-clockwise rotation or wiping action of the cleaning cylinders. Thus, the seed-cotton will be thoroughly cleaned by the time it reaches the vacuum wheel 16 and is discharged through the outlet 15. The leaves and other extraneous matter which pass through the cleaning surfaces 14 drop into the hopper 19 and are carried by the air current through a discharge duct (not shown) which communicates with said hopper.

From the foregoing, it is readily apparent that mechanically-gathered cotton is efficiently and thoroughly cleaned by the conditioner or cleaner which has been described hereinbefore. Although it is preferable to employ the same air for drying the cotton and for subjecting said cotton while

passing through the cleaner to an air stream or suction, the air for the latter purpose could be obtained from any source so long as it was relatively dry and hot. The co-action of the downward blast or current of air and the discontinuous, grate-type cleaning surface together with the wiping action of the cleaning cylinders are the most important and essential elements of the cleaner and could not be successfully eliminated 5 without the substitution of an equivalent arrangement. Of course, the wilting of the green leaves to a soft, flexible or pliable condition is also advantageous, as it tends to prevent said leaves from bridging the fingers, and might be 10 accomplished by any suitable means. This wilting of the leaves facilitates the removal or separation thereof from the cotton in a substantially intact or whole condition, whereby breaking and powdering of said leaves and consequent admixing 15 of the same with the cotton is reduced to a minimum. Obviously, the efficiency of the cleaning action decreases the time thereof, whereby the relative size of the cleaner or the number of cleaning cylinders may be reduced and whereby 20 roping, twisting and machining of the cotton is substantially eliminated. Also, the necessity for the conventional beating action of the cleaning cylinders is obviated, because it is the wiping action of said cylinders which is essential. All of these features are interdependent and 25 coact to produce the new and improved result. Although the cleaner is primarily designed for the cleaning of mechanically-gathered cotton, the same could be employed to clean the usual hand-picked cotton or other fiber.

The foregoing description of the invention is explanatory thereof and various changes in the size, shape and materials, as well as in the details of the illustrated construction may be made, 30 within the scope of the appended claims, without departing from the spirit of the invention.

What I claim and desire to secure by Letters Patent is:

1. A cleaner for cotton admixed with green leaves including, an elongate cleaning chamber open longitudinally throughout the major portion of its top, grate-type arcuate cleaning surfaces disposed in transverse parallel rows longitudinally along the bottom of said chamber, 45 revolving cleaners disposed in the chamber transversely of and above the rows of cleaning surfaces, a major portion of said cylinders being below the top opening, and means for directing a current of air downwardly into the chamber from 50 said top opening onto and between said cylinders for urging extraneous matter through said surfaces.

2. A cleaner as set forth in claim 1, and means at the discharge end of the chamber for preventing the escape of air to cause substantially all of the air to pass down through the grates.

3. A fiber conditioner including, a cleaner having a chamber, means within the chamber for separating extraneous matter from fiber, the separating means having a discontinuous cleaning surface and rotating means disposed adjacent to and coacting with the cleaning surface for receiving the fiber and extraneous matter therebetween, the rotating means moving said fiber and extraneous matter along said cleaning surface, and means for subjecting the fiber and extraneous matter to a current of air directly downward throughout the major portion of the length of the cleaning surface to urge the extraneous matter 65 onto said cleaning surface and through the same

and to provide an even distribution of downward-directed air through the cleaning surface, said cleaning surface being of the grate-type and having a plurality of fingers forming rectangular openings extending longitudinally of the direction of movement of the fiber and extraneous matter for permitting the passage therethrough of the air current and small extraneous matter and also having openings at the free ends of the fingers transverse to such direction of movement for receiving and discharging the large extraneous matter.

4. As a sub-combination in a fiber conditioner, a generally rectangular concaved cleaning member including a plurality of transverse rows of fingers sections having parallel fingers extending longitudinally of the member, some of the sections having the ends of their fingers spaced from

the fingers of adjacent sections to provide elongate transverse openings between the sections.

JOHN BLEWETT.
